PLANT RECEPTACLE

Paul T. Crane, New York, N. Y.

Application March 18, 1953, Serial No. 24,097

Term of patent 14 years

(Cl. D35—3)

To all whom it may concern:

Be it known that I, Paul T. Crane, a citizen of the United States, residing at New York, county of New York, State of New York, have invented a new, original, and ornamental Design for a Plant Receptacle, of which the following is a specification, reference being had to the accompanying drawing, forming a part hereof.

Figure 1 is a front elevation of a plant receptacle showing my new design.

Figure 2 is an end elevation thereof.

Figure 3 is a horizontal section taken on line 3—3 of Figure 1 and looking in the direction of the arrows; and

Figure 4 is a fragmentary vertical section taken

on line 4—4 of Figure 2 and looking in the direction of the arrows.

I claim:

The ornamental design for a plant receptacle, as shown.
